PLOTTING METHOD AND DEVICE

Samuel Gill Gamble, Ottawa, Ontario, Canada,
assignor to His Majesty the King in the right
of Canada, as represented by the Minister of
Mines and Technical Surveys

Application February 14, 1952, Serial No. 271,565

7 Claims. (Cl. 33—1)

1

This invention relates to the art of plotting topographical maps and plans from aerial photographs having stereoscopic overlaps.

In the art of preparing topographical maps, it is common practice to project upon a mapping surface a stereoscopic image from a pair of aerial photographs. It is also common practice to employ in association with such image index means supported on the mapping surface and having a luminous mark by means of which any particular plane in the terrain of the image may be established and the contour thereof traced upon the mapping surface.

It is an object of the present invention to provide a method and means for producing a broad visually transparent plane adjustable to intersect a three dimensional optically projected image at any desired elevation and having thereon a multiplicity of luminous targets in or on the surface of the plane whereby the operator can estimate the position of the plane over the whole surface of the image intersected by the plane. A further object is to produce such a plane on the surface of which the projected images are actually resolved.

The invention will be described with reference to the accompanying drawing in which

Figure 1 is an isometric view of the tracing table of the present invention in association with conventional mapping equipment,

Figure 2 is an enlarged isometric view of the tracing table with parts broken away,

Figure 3 is an enlarged side elevation of the tracing table in slightly modified form, and

Figure 4 is an enlarged sectional view of still another modified portion of the tracing table.

In the drawing, 1 is a mapping stand having a mapping table 2 and a pair of projectors 3 suspended over the table for projection of the stereoscopic image in the usual manner.

The tracing table of the present invention is indicated generally at 4 and comprises a rectangular boxlike frame 5 having mounted therein illuminating means 6 and a flat top member 7 which is generally opaque but which is provided with a multiplicity of very small pin holes or perforations 8 for passage of light therethrough and adapted to constitute the targets of the present invention. The holes or perforations 8 are shown as of exaggerated size in Figs. 2, 3 and 4 of the drawings, and each will normally not be substantially larger than approximately 0.004" in diameter. The holes should occur at intervals not substantially exceeding 0.30 inch throughout the member 7. The size of member

7 may vary within wide limits but 30 inches long by 15 inches wide has been found to provide a satisfactory working surface.

The member 7 may be formed in various ways.

5 As shown in Figure 2, it comprises a glass plate 9 surmounted by an opaque sheet 10 of paper or like material, the holes 8 being formed in the sheet 10. As shown in Figure 3, it may comprise a metal plate 11, having a layer 12 of opaque white paint on its upper surface, the holes 8 extending through the plate and layer. As shown in Fig. 4 it may comprise a glass plate 13 having a layer 14 of opaque white paint on its upper surface, the holes 8 being etched through the paint layer 14.

10 The illuminating means 6 is such as to provide substantially uniform illumination of the under surface of member 7 for production of targets of generally uniform luminosity. As shown, the means may comprise a battery of uniformly spaced electric lamps 15 connected to any suitable source of power by wires 16 through a conventional switch 17 mounted on frame 5. Means such as a transformer 18 having a control knob 19, are preferably provided for adjusting the intensity of the illumination provided by the lamps.

15 The frame 5 is mounted on any suitable supporting means which is adjustable to vary the height and inclination of the frame and member 7 with respect to the mapping table 2 on which it is adapted to be supported. As shown, such means may comprise three legs 20, two at the forward portion of the table and one at the rearward portion. Each leg 20 may comprise a post

20, a sleeve 22 on the post and fixed to the frame 5, and a knurled nut 23 on a lower screw-threaded portion 24 of the post and rotatable to move the sleeve frame in a perpendicular direction. Preferably, a set screw 25 is provided in the sleeve for locking engagement with the post.

25 For wide adjustment, the set screw may be loosened and the frame moved up or down manually, the knurled nut 23 being employed for fine adjustments. An indicating scale 26 may be mounted on each post for accuracy of adjustment.

30 As shown in Figure 3, the electric lamps 15 may be mounted on a separate tray 27 slidably mounted in frame 5 for ease of replacement of the lamps.

35 Means for producing a flow of cooling air through the frame 5 may comprise an opening 28 in the front wall of the frame and a conduit 29 connected to the rear wall of the frame, as shown.

In operation, the drawing material is placed upon the surface of member 1 and the stereoscopic image projected thereupon. With the illuminating means 6 energized, the light targets produced by the holes 8 are adjusted to proper intensity to produce a readily visible plane grid of such targets on the drawing material and intersecting the image. After any necessary adjustment of the member 1 as to inclination to compensate for corresponding inclination in the basic photographs from which the image is produced, the member 1 is adjusted in a perpendicular direction until the luminous grid intersects the three-dimensional image at a desired plane in the terrain thereof. Thereafter the contour of the terrain at such plane is traced directly upon the drawing material using any normal marking device.

It will be observed that, since the mapping material is superimposed on the device, the operator has an entirely unobstructed view of the topography he is mapping. Moreover, the operator employs directly any normal marking device, such as a pen or pencil, for delineating detail on the mapping surface. Therefore, the operator may see what he has previously drawn, and thus avoid inconsistencies in the drawing. Errors in the drawing are also readily detectable and corrected.

The device is subject to convenient and inexpensive manufacture and may be employed with standard types of mapping equipment.

What is claimed is:

1. A method of plotting topographical information which includes the step of projecting a stereoscopic image from a stereoscopic pair of images and which comprises placing in a common plane a multiplicity of visible targets at frequent intervals extending over an area at least as great as that of the major portion of said image, locating said common plane targets in intersecting relation to said stereoscopic image, and plotting detail from said stereoscopic image directly upon mapping material located in said common plane.

2. A topographical plotting device comprising a frame, a flat top member mounted in the frame, lighting devices mounted in the frame below said member and being uniformly arranged to provide substantially uniform distribution of light

upon the lower surface of said member, means for varying the intensity of the light provided by said devices, said member having a multiplicity of pin holes therein for passage therethrough of light from said devices and being otherwise substantially opaque, and legs supporting said frame, at least one of said legs being adjustable as to height to vary the inclination and height of said member.

3. A topographical plotting device as defined in claim 2, said flat top member comprising a glass plate having a layer of opaque paint thereon, said holes being etched in said paint.

4. A topographical plotting device as defined in claim 2, said flat top member comprising a glass plate, and a sheet of opaque material superimposed on said plate, said holes being formed in said sheet.

5. A topographical plotting device comprising a frame, a flat top member mounted in the frame, a plurality of electrical lighting devices mounted in the frame below said member, said devices being uniformly arranged to provide substantially uniform distribution of light upon the lower surface of said member, means for varying the intensity of the light provided by said devices, said member having a multiplicity of pin holes therein for passage therethrough of light from said devices and being otherwise opaque, and supporting legs fixed to said frame, each said leg being adjustable as to height to vary the inclination and height of said member.

6. A topographical plotting device as defined in claim 5, said holes being spaced apart not substantially more than approximately 0.30 inch.

7. A topographical plotting device as defined in claim 5, each said hole having a diameter not substantially exceeding 0.004 inch.
